CIRCUIT INTERRUPTER

Edwin E. Arnold, Pittsburgh, Pa., assignor to
Westinghouse Electric Corporation, East Pitts-
burgh, Pa., a corporation of Pennsylvania

Application January 7, 1943, Serial No. 471,555

20 Claims. (Cl. 200—150)

This invention relates to circuit interrupters in general and, more particularly, to arc extinguishing structures and operating mechanisms therefor.

More particularly, it is an object of my invention to effect rapid arc extinction by utilizing a pump means actuated by at least a portion of the series current passing through the interrupter.

Another object of my invention is to provide an improved circuit interrupter having improved and more effective contact structure.

Another object is to provide an improved circuit interrupter having a plurality of contact members and connecting fluid moving means electrically between two of the contact members.

Another object is to provide an improved circuit interrupter comprising a plurality of contact members which separate sequentially during the opening operation of the interrupter, and to electrically connect a fluid moving means between two of the contact members to force an arc extinguishing fluid through the arc which is drawn during the opening operation to effect the extinction thereof.

A more specific object of my invention is to provide an improved circuit interrupter having three contact members engaging each other in abutting relation in the closed circuit position. A fluid moving means is electrically connected between two of the contact members, and the third contact member is operable to draw an arc which is rapidly quenched by the operation of the fluid moving means.

Another object is to provide an improved contact structure in which the intermediate contact is flexibly supported on a flexible diaphragm. The diaphragm may be employed during the opening operation of the interrupter to effect initial fluid motion to extinguish the arc drawn. The arrangement is especially desirable during the interruption of low currents.

Another object is to provide an improved arc extinguishing unit in which a coil is connected in series circuit during the opening operation to move a ring-shaped piston to effect fluid motion for the extinction of the arc drawn during the opening operation of the interrupter. Preferably the contact structure is so arranged that the coil is not shorted out during the elongation of the arc drawn during the opening operation.

Another object is to provide an arc extinguishing unit with an improved operating means for the movable contact structure.

A further object is to provide an improved arc extinguishing assemblage comprising a plurality of arc extinguishing units, each of which has improved operating means, the arrangement being such that the moving contacts in all of

the arc extinguishing units are actuated simultaneously.

A further object is to provide an improved circuit interrupter having means actuated by at least a portion of the series current to effect rapid closure of the contact structure during a closing operation with voltage on the line.

Further objects and advantages will readily become apparent upon a reading of the following description taken in conjunction with the drawings in which:

Figure 1 is an elevational view, partially in section, of a complete circuit interrupter embodying my invention, the interrupter being shown in the closed-circuit position;

Fig. 2 is an enlarged elevational view in section of the top arc extinguishing unit shown in Fig. 1, the interrupter being in the closed-circuit position;

Fig. 3 is a view similar to Fig. 2 except showing the interrupter in the open-circuit position; and

Fig. 4 is a view in cross section taken on the line IV—IV of Fig. 2.

Referring to the drawings and in particular to Fig. 1, the reference numeral 1 designates a tank filled to the level 2 with a suitable arc extinguishing fluid, in this instance oil. Suspended from the cover 3 of the tank 1 are two bushings 4, 5 each having attached to its lower end an arc extinguishing assemblage generally designated by the reference numeral 6.

A conducting bridging member 7 actuated by an insulating lift rod 8 and arranged for longitudinal reciprocating motion serves to electrically connect the arc extinguishing assemblages 6 in the closed circuit position of the interrupter as shown in FIG. 1.

Each arc extinguishing assemblage 6 comprises a plurality, in this instance three, arc extinguishing units generally designated by the reference numeral 9. Surrounding the three arc extinguishing units 9 in each arc extinguishing assemblage 6 is an insulating cylindrical shield 10. At its upper end is a metallic electrostatic shield 11 to minimize corona formation, and at its lower end is also a metallic electrostatic shield 11a which also minimizes corona formation.

It will, therefore, be apparent that the electrical circuit through the interrupter passes through a terminal conductor located centrally within the insulating bushing 4, not shown, to the upper arc extinguishing unit 9, whence the circuit passes through the intermediate arc extinguishing unit 9 to the lower arc extinguishing unit 9. The circuit then extends through the conducting bridging member 7 to the right-hand arc extinguishing assemblage 6 to the other line terminal of the interrupter.

The movable contact structure within each arc extinguishing unit 8 is actuated by an insulating operating rod 12 which is actuated by the conducting bridging member 7 during the opening and closing operations of the interrupter.

Referring more particularly to Fig. 2, which shows the upper arc extinguishing unit 8, it will be observed that the upper arc extinguishing unit 8 comprises a top metallic dome 13 which is secured, as by the stud bolts 14, to an insulating top plate 15 and to an insulating casing 16. The insulating top plate 15 supports an annular stationary contact 17 having an annular arc-resisting portion 18 composed of a suitable arc resisting material. Making contact with the annular arc-resisting portion 18 in the closed-circuit position of the interrupter is a nozzle-shaped intermediate contact 19 having an upper annular arc-resisting portion 20 which engages the annular arc-resisting portion 18 of the stationary contact 17 in the closed-circuit position of the interrupter as shown in Fig. 2.

The nozzle-shaped intermediate contact 19 is resiliently supported by a flexible metallic diaphragm 21. The outer periphery of the metallic diaphragm 21 is rigidly secured to the insulating casing 16. Cooperating with a lower annular arc-resisting portion 22 of the nozzle intermediate contact 19 is a rod-shaped lower movable contact 23 guided in its reciprocal longitudinal motion by an insulating guide member 24. The lower end of the movable contact 23 is in this instance enlarged to form a substantially square block member 25. The block member 25 is connected by a pin 26 to two links 27, the other ends of which are pivotally connected by a knee pin 28 to two actuating link members 29 and to two link members 30. The lower ends of the two link members 30 are pivotally supported by the pin 31. A bell crank 32 pivotally mounted on the pivot pin 33 and pivotally connected by the pivot pin 33a to the links 28 has a bifurcated portion 34 to which is pivotally mounted by the pin 35 the insulating operating rod 12. It will, consequently, be seen that downward motion of the insulating operating rod 12 results in clockwise rotation of the bell crank 32 about the pivot pin 33 to result in the two actuating link members 29 being moved toward the right to break the toggle comprising the links 27, 30 to effect a downward movement of the movable contact 23. The position of the various structural parts in the open circuit position is more clearly shown in Fig. 3, Fig. 2 showing the position of the parts in the closed-circuit position of the interrupter.

A compression spring 36 biases the bell crank 32 in a clockwise direction as viewed in Fig. 2, which biasing action tends to move the movable contact 23 to the open circuit position.

A plurality, in this instance two, roller members 37 positioned in recesses formed in the block member 25 roll along a vertical surface 38 provided by the lower metallic casting 39. It will be observed therefore that the lateral stress on the block member 25 acting toward the left during the closing of the interrupter is relieved by the roller members 37 rolling along the vertical surface 38. Consequently, the aperture 40 provided in the insulating guide member 24 is not deformed to result in a leakage of fluid adjacent the upper end of the movable contact 23 through the aperture 40 and out of the arcing chamber generally designated by the reference numeral 41.

The lower metallic casting 39 is clamped by

the stud bolts 42 to the insulating casing 16. The stud bolts 42 also secure a lower insulating member 43 to the insulating casing 16. Rigidly positioned within a recess 44 provided in the lower insulating member 43 is a repulsion coil 45 composed of an insulation-covered metallic conductor wound in a spiral manner or pan cake coil. One end of the repulsion coil 45 is connected by the conducting strap 46 to the metallic diaphragm 21 and hence to the nozzle shaped intermediate contact 19. The other end of the repulsion coil 45 is connected by the conducting strap 47 to the stud bolt 14 and hence electrically to the metallic dome member 13. The annular stationary contact 17 is connected electrically by a strap 48 to the bolt 49 and thence by means of the conducting strap 50 to the stud bolt 14.

It will, consequently, be apparent that the repulsion coil 45 is connected between the annular stationary contact 17 and the nozzle-shaped intermediate contact 19. Positioned immediately above the repulsion coil 45 is a ring-shaped conducting plate 51 biased downwardly by the compression springs 52 and secured to a metallic piston 53. It will be hereinafter explained, that upon energization of the repulsion coil 45 the ring-shaped plate 51 will be forcibly repelled upward against the biasing action of the compression springs 52 to put the fluid within the arcing chamber 41 under pressure. Vents 54 and 55 permit unimpeded motion of the ring-shaped plate 51 and the piston 53.

In the closed-circuit position of the interrupter, as shown in Fig. 2, the electrical circuit therethrough comprises the metallic dome casting 13, stud bolt 14, conducting strap 46, bolt 49, conducting strap 48, annular stationary contact 17, intermediate contact 19, movable contact 23, block member 25, bolt 49, conducting strap 57 to the bolt 49 of the intermediate arc extinguishing unit 8, from whence the circuit passes in an identical manner therethrough to the lower arc extinguishing unit 8 (refer to Fig. 1). The electrical circuit passes from the conducting strap 57 associated with the lower arc extinguishing unit 8 of Fig. 1 to the disconnect fingers 58 which make engagement in the closed-circuit position of the interrupter, as shown, with the movable conducting bridging member 7.

The opening operation of the interrupter will now be described. During the opening operation the insulating lift rod 8 is moved downwardly by suitable operating mechanism not shown to permit downward motion of the insulating operating rod 12, the latter being biased downwardly by the compression springs 36. During the downward movement of the insulating operating rod 12 the conducting bridging member 7 remains in contact with the disconnect fingers 58 associated with the lower arc extinguishing unit 8. The downward movement of the insulating operating rod 12 causes a clockwise rotation of the bell cranks 32 to result in the downward movement of the movable contacts 23 in a manner previously described. It will therefore be apparent that the initial downward movement of the insulating operating rod 12 causes a simultaneous downward movement of the respective movable contacts 23 associated with the several arc extinguishing units 8.

The initial downward movement of the movable contacts 23 causes a separation between the stationary contacts 17 and the intermediate contacts 19 as shown more clearly by the dotted lines in Fig. 3. The separation between the stationary

contact 17 and the intermediate contact 19 causes the series current through the interrupter to pass through the repulsion coil 45. At this point during the opening operation of the interrupter, referring to Fig. 3, the electrical circuit therethrough comprises the metallic dome casting 13, stud bolt 14, conducting strap 47, repulsion coil 45, conducting strap 46, diaphragm 21, intermediate contact 19, movable contact 23, block member 25, bolt 56, conducting strap 57, bolt 49 of the intermediate arc extinguishing unit 9, conducting strap 60 to bolt 14 of the intermediate arc extinguishing unit 9 from which the circuit passes in an identical manner as that previously described through the two lower arc extinguishing units 9 to the disconnect fingers 58 and to the conducting bridging member 7. The circuit passes through the righthand arc extinguishing assemblage 6 (see Fig. 1) in an identical manner to the righthand line terminal of the interrupter.

When the stationary contact 17 separates from the intermediate contact 19 and the repulsion coil 45 is consequently put in series circuit, the ring-shaped plate 51 has induced therein an alternating current which is substantially 180 electrical degrees out of phase with the alternating current passing through the repulsion coil 45. The induced current in the ring-shaped plate 51 causes it to be violently forced upward against the biasing action of the compression springs 52 to force the piston 53 upward and hence to put the fluid within the arcing chamber 41 under pressure. It will also be observed that during this time the diaphragm 21 has moved downward and hence has also tended to put the fluid within the arcing chamber 41 under pressure. Consequently, by the time the movable contact 23 separates from the intermediate contact 19, a forceful jet of arc extinguishing fluid, in this instance oil, washes across the top surface of the movable contact 23 to extinguish the arc which is drawn between the movable contact 23 and the intermediate contact 19 and which is designated by the reference numeral 59 in Fig. 3.

Consequently the pressure of the fluid within the arcing chamber 41 causes a flow of fluid upward through the nozzle-shaped intermediate contact 19 to effect the rapid extinction of the arc 59. When the arc 59 is extinguished the circuit through the interrupter is broken and the compression springs 52 return the ring-shaped plate 51 to its lower position adjacent the repulsion coil 45. After the electrical circuit is broken through the interrupter the conducting bridging member 7 separates from the disconnect fingers 58 (see Fig. 1) to introduce two isolating gaps in the circuit.

It will be observed that during the interruption of high short-circuit currents the consequent repelling action between the repulsion coil 45 and the ring-shaped plate 51 will be very violent, and the fluid within the arcing chamber 41 will be under high pressure to effect a rapid flow through nozzle 19 and extinction of the arc 59. During the interruption of low currents the repelling action between the repulsion coil 45 and the ring-shaped plate 51 will not be so violent, and in this instance it will be observed that the downward movement of the diaphragm 21 will put the requisite amount of fluid in the arcing chamber 41 under pressure to effect the interruption of the arc 59 during the interruption of low currents. As shown in the drawings, the

downward movement of the diaphragm 21 displaces roughly 15% of the fluid displaced by the piston 53. This displacement of the fluid caused by the downward movement of the diaphragm 21 is independent of the current value and is, as mentioned previously, useful for interrupting low-value currents where the repulsion coil 45 is not so effective.

It will be observed that during the closing operation of the interrupter with voltage on the line the movable contact 23 will move upward to strike the intermediate contact 19 to cause the insertion of the repulsion coil 45 in series circuit before the intermediate contact 19 strikes the stationary contact 17. Thus during the closing operation the repulsion coil 45 will be energized and will repel the ring-shaped plate 51 upward to put the fluid within the arcing chamber 41 under pressure. This sudden rise in pressure during the closing operation will flex the diaphragm 21 upward to increase the upward speed of the intermediate contact 19 and hence to increase the speed with which the intermediate contact 19 approaches the annular stationary contact 17. Consequently, I have used a means utilizing a part of the energy passing through the interrupter to speed up the closing of the contact structure during a closing operation with voltage on the line. When the intermediate contact 19 strikes the stationary contact 17 during the closing operation, the repulsion coil 45 will be shorted out, and the ring-shaped plate 51 will be forced to its lower position by the compression springs 52. The interrupter will then be in the closed-circuit position as shown in Fig. 2, and the ring-shaped plate 51 will be at its lower position ready for the next opening operation.

It will be observed that the intermediate contact 19 has an upstanding portion 60, which in this instance extends completely through the annular stationary contact 17. The upstanding portion 60 is provided so that the arc 59, which is drawn during the opening operation, will not be blown through the intermediate contact 19 to have its upper terminal reach the stationary contact 17. If this occurred the repulsion coil 45 would be shorted out and hence would be rendered ineffective. Consequently, by providing the upstanding portion 60 the arc 59 is prevented from contacting the stationary contact 17 and shorting out the repulsion coil 45.

Vents 62 in the plate 15 permit free movement of the diaphragm 21.

It will be observed that immediately above the diaphragm 21 is an annular surface 61. The annular surface 61 has a twofold purpose. First it offers support and safety against overstressing the diaphragm 21. Secondly, the contour of the surface 61 is such as to follow the natural deflection curve of the diaphragm 21 loaded uniformly, that is, from the hydrostatic oil pressure on the inner surface of the diaphragm 21. Such a deflection curve for a given total uniform loading is flatter and of less maximum amount at the center of the diaphragm 21 than would result from the same total load being applied at the center of the diaphragm 21. The result of this design provision is that contact may not be made between the stationary contact 17 and the intermediate contact 19 and therefore the repulsion coil 45 may not be shorted out by pressure alone, but will require additional pressure applied at the center of the diaphragm 21 by the moving contact 23 to effect the final contact between the

intermediate contact 19 and the stationary contact 11.

As mentioned previously, when the interrupter is used on alternating current the induced current in the ring-shaped plate 51 is substantially 180 electrical degrees out of phase with the current through the repulsion coil 45. This difference in phase produces a violent repellent action between the coil 45 and the plate 51. When the interrupter is used on a direct current circuit the increase in current through the coil 45 will also induce a current through the plate 51 to effect a similar repelling action, although of not as long duration as in the case of an alternating current circuit. However, it is to be clearly understood that my invention is applicable not only to alternating current circuits but to direct current circuits as well. Furthermore, it is to be understood that in place of the repulsion coil 45 and the piston 53 secured to the plate 51, I may use other fluid moving pump arrangements actuated by at least a portion of the series current through the interrupter. By my showing only a particular form of electrically actuated fluid moving means, it is not to be understood that my invention is limited to the particular form shown. Other fluid moving means, such as, for example, a solenoid pump arrangement may be used in place of repulsion coil 45.

Although I have shown an application of my invention associated with a liquid-type circuit interrupter, it is to be clearly understood that my invention may be applied to other types of circuit interrupters, such as those operating in a gaseous medium or even in air. The term fluid as used herein and in the appended claims comprises liquids, vapors, gases and sprays.

Although I have shown a specific form of circuit interrupter, it is to be clearly understood that the same was merely for the purpose of illustration and that changes and modifications may be made by those skilled in the art without departing from the spirit and scope of the appended claims.

I claim as my invention:

1. In a circuit interrupter, a first relatively stationary contact member, a second intermediate contact member, a third movable contact member, means resiliently mounting the second intermediate contact member, the three contact members engaging each other in abutting relation in the closed circuit position of the interrupter, a fluid moving means electrically connected between the first relatively stationary contact member and the second intermediate contact member, and means for causing the separation of the three contact members to insert the fluid moving means in series circuit.

2. In a circuit interrupter, a first relatively stationary contact member, a second intermediate contact member, a third movable contact member, means resiliently mounting the second intermediate contact member, the three contact members engaging each other in abutting relation in the closed circuit position of the interrupter, a fluid moving means electrically connected between the first and second contact members, and means for causing the sequential separation of the three contact members to insert the fluid moving means serially in the circuit before the subsequent separation of the second and third contact members.

3. In a circuit interrupter, a first relatively stationary contact member, a second intermediate

contact member, a third movable contact member, means resiliently mounting the second intermediate contact member, the three contact members engaging each other in abutting relation in the closed circuit position of the interrupter, a fluid moving means electrically connected between the first and second contact members, and means for causing the sequential separation of the three contact members to insert the fluid moving means serially in the circuit before the subsequent separation of the second and third contact members, an arc being drawn upon the separation of the second and third contact members, the fluid moving means helping to extinguish the arc.

4. In a circuit interrupter, a first contact member, a second contact member, a third contact member, the three contact members engaging each other in abutting relation in the closed circuit position of the interrupter, a fluid moving means electrically connected between the first and second contact members, and means for causing the sequential separation of the three contact members to insert the fluid moving means serially in the circuit before the subsequent separation of the second and third contact members, an arc being drawn upon the separation of the second and third contact members, the fluid moving means helping to extinguish the arc, the second contact member being formed as a nozzle to shield the first contact member from the arc.

5. In a circuit interrupter, a first contact member, a second contact member, a third contact member, the three contact members engaging each other in abutting relation in the closed circuit position of the interrupter, a fluid moving means electrically connected between the first and second contact members, and means for causing the sequential separation of the three contact members to insert the fluid moving means serially in the circuit before the subsequent separation of the second and third contact members, an arc being drawn upon the separation of the second and third contact members, the fluid moving means helping to extinguish the arc, the second contact member being formed as a nozzle to shield the first contact member from the arc, the second contact member being supported on a flexible diaphragm.

6. In a circuit interrupter, a first contact member, a second contact member, a third contact member, the three contact members engaging each other in abutting relation in the closed circuit position of the interrupter, a fluid moving means electrically connected between the first and second contact members, and means for causing the sequential separation of the three contact members to insert the fluid moving means serially in the circuit before the subsequent separation of the second and third contact members, an arc being drawn upon the separation of the second and third contact members, the fluid moving means helping to extinguish the arc, the second contact member being formed as a nozzle to shield the first contact member from the arc, the second contact member being supported on a flexible diaphragm, the flexible diaphragm being arranged to cause additional fluid motion.

7. In a circuit interrupter, a substantially enclosed arcing chamber having one wall thereof formed by a metallic diaphragm, an annular relatively stationary contact, an intermediate contact flexibly mounted on the metallic diaphragm, and a movable rod-shaped contact mov-

able within the arcing chamber which forces the intermediate contact against the stationary contact in the closed circuit position of the interrupter.

8. In a circuit interrupter, a substantially enclosed arcing chamber having one wall thereof formed by a metallic diaphragm, an annular relatively stationary contact, a nozzle-shaped intermediate contact flexibly supported on the metallic diaphragm, and a rod-shaped movable contact movable within the arcing chamber and operable to force the intermediate contact in abutting relation with the stationary contact in the closed circuit position of the interrupter.

9. In a circuit interrupter, an annular relatively stationary contact, an intermediate contact having a nozzle portion which extends at least part way through the annular stationary contact in the closed circuit position of the interrupter, a movable contact which engages the intermediate contact in the closed circuit position to force the latter against the stationary contact.

10. In a circuit interrupter, a substantially enclosed arcing chamber having one wall thereof formed by a metallic diaphragm, an annular relatively stationary contact, an intermediate contact having a nozzle portion which extends at least part way through the annular stationary contact in the closed circuit position of the interrupter, a movable contact movable within the arcing chamber which engages the intermediate contact in the closed circuit position to force the latter against the stationary contact, the intermediate contact being flexibly supported on the metallic diaphragm.

11. In a circuit interrupter, an annular relatively stationary contact, a nozzle-shaped intermediate contact flexibly supported on a metallic diaphragm, a movable rod-shaped contact cooperating with the intermediate contact to establish an arc, a repulsion coil connected between the stationary and intermediate contacts, and an annular piston ring operable upon energization of the repulsion coil to cause fluid motion through the nozzle-shaped intermediate contact to effect the extinction of the arc.

12. In a circuit interrupter, an annular relatively stationary contact, a nozzle-shaped intermediate contact flexibly supported on a metallic diaphragm, a movable rod-shaped contact cooperating with the intermediate contact to establish an arc, a repulsion coil connected between the stationary and intermediate contacts, and an annular piston ring operable upon energization of the repulsion coil to cause fluid motion through the nozzle-shaped intermediate contact to effect the extinction of the arc, the diaphragm being operable to effect additional fluid motion through the nozzle-shaped intermediate contact to effect quick extinction of the arc on low current interruption.

13. In a circuit interrupter, a substantially enclosed arcing chamber having one wall thereof formed by a metallic diaphragm, an annular relatively stationary contact, an intermediate contact flexibly mounted on the metallic diaphragm, and a movable rod-shaped contact movable within the arcing chamber which forces the intermediate contact against the stationary contact in the closed circuit position of the interrupter, and a support for the diaphragm to prevent the rupture thereof on extremely high pressure.

14. In a circuit interrupter, a substantially

closed arcing chamber having an annular stationary contact forming an outlet, an annularly-shaped intermediate contact flexibly supported on a diaphragm, and a movable contact operable to force the intermediate contact against the stationary contact in the closed circuit position of the interrupter.

15. In a circuit interrupter, a substantially closed arcing chamber having an annular stationary contact forming an outlet, an annularly-shaped intermediate contact flexibly supported on a diaphragm, a movable contact operable to force the intermediate contact against the stationary contact in the closed circuit position of the interrupter, and a fluid moving means electrically connected between the stationary and intermediate contacts.

16. In a circuit interrupter, a substantially closed arcing chamber having an annular relatively stationary contact forming an outlet, a nozzle-shaped intermediate contact which extends at least part way through the annular stationary contact in the closed circuit position of the interrupter, a flexible diaphragm, the intermediate contact being flexibly supported on the diaphragm, and a movable contact operable to force the intermediate contact against the stationary contact in the closed circuit position.

17. In a circuit interrupter, a substantially closed arcing chamber having an annular relatively stationary contact forming an outlet, a nozzle-shaped intermediate contact which extends at least part way through the annular stationary contact in the closed circuit position of the interrupter, a flexible diaphragm, the intermediate contact being flexibly supported on the diaphragm, a movable contact operable to force the intermediate contact against the stationary contact in the closed circuit position, and a fluid moving means electrically connected between the stationary and intermediate contacts.

18. In a circuit interrupter, a flexible diaphragm, a substantially closed arcing chamber having one wall thereof formed by the diaphragm, an annularly-shaped intermediate contact supported by the diaphragm, a stationary contact, a movable contact movable into the arcing chamber to force the intermediate contact into engagement with the stationary contact in the closed circuit position.

19. In a circuit interrupter, a flexible diaphragm, a substantially closed arcing chamber having one wall thereof formed by the diaphragm, an annularly-shaped intermediate contact supported by the diaphragm, a stationary contact, a movable contact movable into the arcing chamber to force the intermediate contact into engagement with the stationary contact in the closed circuit position, and a fluid moving means electrically connected between the stationary and intermediate contacts.

20. In a circuit interrupter, means for establishing an arc, fluid moving means for moving fluid to help extinguish the arc, energy storing means for storing energy during the closing operation, the stored energy being used during the opening operation to help actuate the fluid moving means, and electrical means utilizing at least a portion of the current passing through the interrupter during the closing operation to store energy in the energy storing means.
